Primary Examiner — Robert M. Spear(57) **CLAIM**

The ornamental design for a sticker, as shown and described.

DESCRIPTION

1. Sticker

1.0 : Front

The sticker is made of paper or synthetic resin; the sticker is used to teach fingering by attaching it to string instruments such as violins, violas, and guitars; the sticker is flat; the back view of the sticker is unornamented and therefore not illustrated.

1 Claim, 1 Drawing Sheet
